UNITED STATES PATENT OFFICE.

CORNELIUS VAN DYKE BENNETT, OF VICTOR, NEW YORK, ASSIGNOR TO THE LOCKE INSULATOR MANUFACTURING COMPANY, OF VICTOR, NEW YORK, A CORPORATION, OF NEW YORK.

DIE FOR INSULATORS.

1,157,612.

Specification of Letters Patent. Patented Oct. 19, 1915.

Application filed June 9, 1913. Serial No. 772,580.

To all whom it may concern:

Be it known that I, CORNELIUS VAN DYKE BENNETT, of Victor, in the county of Ontario and State of New York, have invented 5 certain new and useful Improvements in Dies for Insulators; and I do hereby declare the following to be a full, clear, and exact description of the same, reference being had to the accompanying drawings, forming a 10 part of this specification, and to the reference-numerals marked thereon.

The present invention relates to improvements in dies, having particular reference to dies for molding insulators of the type embodying a flange provided with a centrally disposed neck and a series of downwardly projecting petticoats disposed concentrically on the lower face of the flange, and it has for its object to provide a construction which 15 will enable the die to be removed readily from the plastic material after the article is molded. A further object of the invention is the provision of a structure whereby petticoats of any desired thickness be formed on 20 the insulator in a ready manner, and without weakening the insulator at the points where the petticoats join the flanges.

Another object of the invention is the provision of an improved device of this character capable of producing threads on the 25 interior of the central neck on the flange.

To these and other ends the invention consists in certain improvements and combinations of parts all as will be hereinafter more 30 fully described, the novel features being pointed out in the claims at the end of the specification.

In the drawings: Figure 1 is a top plan view of a die constructed according to a preferred embodiment of the present invention, a portion appearing in section; Fig. 2 is a sectional view taken substantially on the line $x-x$ of Fig. 1, and showing the die mounted on a rotary head, and Fig. 3 is a 40 detail sectional view showing a portion of one of the yieldably supported sections of the die.

Similar reference numerals throughout the several figures indicate the same parts.

50 The invention, as illustrated in the present embodiment, includes a support 1 which is attached in any suitable manner to a rotary and vertically movable head 2, whereby the necessary movement is imparted to the die

for forming the insulator, as will be herein-after described more fully. The support 1 carries the body portion of the die, and to this end, is threaded interiorly to receive the downwardly projecting central member 3 which has a shoulder 4 supporting the annular section or groove forming member 5, the latter being provided with an upstanding collar 6 to engage a corresponding recess in the support 1. In addition to the central member 3 and the groove forming member 5, the body portion of the die embodies a series of concentrically arranged rings or groove forming members 7 which are suitably mounted on the support 1 in the following manner. Said support is 15 threaded exteriorly at its lower end, and attached thereto is the spider 8 provided with the arms 9 and the base 10, the latter being recessed on its lower face to receive the flanges 11 on the rings 7, the latter being attached to the spider in any suitable manner, as by means of the screws 12. The spider 8 is provided with annular openings 13 which communicate with spaces formed between the respective annular groove forming members 7, so as to provide an atmospheric communication for the grooves between the rings that form the petticoats on the insulator.

The working face of the body portion of the die is provided with a plurality of members or sections, yieldably mounted to move in a direction substantially transverse to the plane of the working face, and to this end the groove forming members 5 and 7 carry 20 a series of annular members' sections 14, each of which is arranged concentrically about the central member and is normally seated in a recess provided for this purpose in the groove forming members. Each member 14 is supported on a series of plungers 15, the latter being movable in openings in the rings, being held in normal position by means of springs 16 coöoperating with shoulders 17, and collars 18 arranged on the plungers. By this construction, the members 14 are permitted a slight movement downwardly relatively to the body portion of the die so that as the latter is withdrawn from the plastic material after stamping the desired article, the members 14 will remain in contact with the plastic for a slight period longer than the stationary part of the work-

ing surface of the die, and until sufficient air is admitted through the openings 13 to fill around the movable members, and thus permit a ready release of the entire die without weakening or marring in any way the finished surface of the article. By the provision of the air openings 13 which permit entrance of air to the upper edges of the petticoats of the insulator, the latter can be made much thinner than by a die constructed in any other manner, and it is unnecessary to reinforce or thicken the petticoats at any part in order to overcome possibility of their breaking as the die is withdrawn.

15. The cast or mold is designated at 19, and 20 is the plastic substance to be formed into an insulator of a well known type. In the operation, the die is moved downwardly to engage the plastic material and is rotated 20 simultaneously so as to produce the interior threads on the central neck of the insulator, this being accomplished by the threaded lower end of the central member 3. The central member 3 is preferably hollow, and is 25 closed at its lower end by a suitable relatively movable section, comprising in the present instance a plunger 21 adapted normally to engage the end of the sleeve 22 that is secured within the member 3. The plunger 30 21 carries a collar 23 at its upper end and is adapted to be held in normal position by means of a spring 24 coöperating with said collar and with the shoulder on the sleeve 22. Thus, as the die is withdrawn from 35 the molded article, the plunger 21 is retained for an instant in engagement with the plastic material, moving relatively to the central member as the latter is raised and rotated. Immediately air enters and surrounds the

lower end of the plunger 21, permitting its 40 ready release from the plastic.

I claim as my invention:

1. In a die of the type described, a central member and a plurality of concentric groove forming members, each provided on its forward edge with a channel in which is yieldingly mounted an annular member, movable in a direction transverse to the working face of the die, whereby said annular member may adhere to the formed body while the remainder of the die is retracted a short distance. 45

2. In a die of the type described, a central member and an annular groove forming member substantially concentric therewith, said annular groove forming member provided on its forward edge with a channel in which is mounted an annular member, movable in a direction transverse to the working face of the die, whereby said annular member may adhere to the formed body while the remainder of the die is retracted a short distance. 50

3. In a die of the type described, a central member and an annular groove forming member substantially concentric therewith, said annular groove forming member having its forward edge formed of an annular member movable in a direction transverse to the working face of the die whereby said annular member may adhere to the formed body while the remainder of the die is retracted a short distance to admit air to the formed groove. 65

CORNELIUS VAN DYKE BENNETT.
